RAIL JOINT PARTING GRINDER

Samuel Oldham, Chicago, and Frank C. Hasse, La Grange, Ill., assignors to The Oxweld Railroad Service Company, a corporation of Delaware

Application December 27, 1928
Serial No. 328,711

3 Claims. (Cl. 51—178)

This invention pertains to grinding machines and more specifically to such a machine that is adapted for being transported along a railroad track and used to grind out the joints between

5 rail ends.

When railroad rails are in service the ends wear much faster than the rest of the rail on account of the hammering they receive as the car wheels pass over the joints or spaces between 10 the ends of adjoining rails. When the ends of rails become worn it has been found that their life may be lengthened by building up the worn rail ends by one of the fusion welding processes and then grinding the added metal down to the 15 original contour line of the rail. In building up the ends of the rails the joint or space between their ends is frequently filled with metal so that there is not enough space between the rail ends to allow for expansion. Heretofore, this metal 20 has been removed from the joints by means of a cold chisel or hacksaw but this method is unsatisfactory as the added metal is frequently too hard to be worked in this manner so that process is slow, expensive, and the result only partially 25 satisfactory.

Therefore, one of the objects of this invention is to provide a machine that will remove weld metal from rail joints in a quick, economical, and satisfactory manner.

30 When the steel in railroad rails is hard enough to withstand the hammering of car wheels without deforming at the ends where the wheels strike the sharp corner of the rails it has been found that the impact of the wheels frequently 35 breaks portions from the upper corners of the rail ends thereby increasing the width of the joint to an undesirable extent. It has been found that by removing a small amount from the upper corners of the rail ends that this breakage 40 is prevented.

Therefore, another object of this invention is to provide a machine for removing the upper corner of rail ends in a quick and economical manner. Other aims and objects of this invention will be apparent from the drawings and the following description.

We attain the above mentioned objects of the present invention by the apparatus shown in the accompanying drawings, in which:

50 Fig. 1 is a side elevation of our rail joint parting machine;

Fig. 2 is an end elevation of the same, and;

Fig. 3 is a section through the free end of the flexible shaft showing the method of mounting 55 the emery wheel.

The rail joint parting machine shown in the drawings may comprise a cradle A, a power plant B in the cradle A, and a flexible shaft C having an emery wheel mounted on the free end thereof, and the fixed end thereof attached to the cradle 60 A and arranged so that the power plant will drive the emery wheel therethrough.

The cradle A may comprise two integral analogous or similar U-shaped angle iron sections or frame members 10 and 11, having horizontal parallel bottom portions or sections 10a and 11a respectively and upturned or uprising ends or legs 10b and 11b respectively. Secured to the upturned ends 10b and 11b by any convenient means such as the bolts 12 are two shackles 13 and 14 70 that hold the sections 10 and 11 of the cradle A side by side so that the top of the sections 10 and 11 are closer together than the bottom. Near the center of the shackles 13 and 14, and extending upward from the top of the upturned ends 10b and 11b are two loops 13a and 14a respectively, that encircle a suitable length of iron pipe or bar 15, to which the loops 13a and 14a are 75 clamped by the bolts 16. The pipe 15 extends parallel to the central plane of the cradle through 80 the shackles 13 and 14 beyond the ends 10b and 11b of the sections 10 and 11 and forms a handle by which the cradle may be carried. Secured to the upturned ends of the sections 10 by means of the bolts 17 is a guard 18, and secured to the 85 upturned ends of the section 11 by means of the bolts 19 is a guard 20 similar to the guard 18. Each of the guards 18 and 20 extend outward from one of the uprising ends of one of the sections 10 and 11 and then across and back to the 90 other uprising end of the same section thereby preventing persons from coming in contact with the sides of the power plant B that is in the cradle and will be described presently.

Positioned in the cradle A and secured to the 95 horizontal bottom portions 10a and 11a thereof, by any suitable means such as the bolts 21, is a self contained, portable, unitary, gasoline engine power plant B. The power plant B may comprise a gasoline engine of the air cooled type 100 having cooling fans, gasoline tank, carburetor, muffler, and magneto, assembled in a compact portable unit. Other power plants or sources of power may, however, be used in place of that described and shown herein.

105 The flexible shaft C may comprise a flexible casing 24 with a countershaft 25 attached to one end, and a spindle or handpiece 26 attached to the other end. Secured to one of the uprising ends 10b and 11b of each of the sections 10 and 11 110

of the cradle A, by any suitable attaching means such as the bolts 21, is a cross member 22 having a socket 23 in which the fixed end of the flexible shaft C is secured. The interior of the socket 23 5 may be threaded to receive a threaded support 27 extending downward from the under side of the countershaft 25, so that the support 27 may be moved either up or down in the socket 23 to vary the tension of the driving belt to be described 10 later. A set screw 28 is threaded in the wall of the socket 23 so it may be forced against the support 27 to hold it in any adjusted position in the socket. It is understood, of course, that the support 27 may slide loosely in the socket 23 instead 15 of being threaded therein, and the support may be clamped in the socket by means other than the set screw shown.

Secured to the outer end of the crankshaft of the power plant B is a V-belt cone pulley 29, 20 and secured to the countershaft 25 is another V-belt cone pulley 30. The socket 23 is positioned so it supports the countershaft 25 with the pulley 30 attached thereto in alignment with the pulley 29 attached to the power plant. Upon the 25 pulleys 29 and 30 is a V-belt 31. The flexible shaft in its complete form may comprise the countershaft 25, spindle 26, and the casing 24 with a shaft therein. Other flexible shaft assemblies may, however, be used in place of the one 30 described. Also, pulleys of other styles may be used as well as a belt that is different from that shown and described.

Mounted on the spindle 26 at the free end of the flexible shaft C is an emery wheel 32. The 35 method of mounting is shown more clearly in Fig. 3. In order to enter the joint between the adjoining ends of railroad rails the emery wheel 32 must be quite thin. Thin emery wheels, especially when held in the hand during use, are liable to frequent breakage. For the purpose of parting rail joints we have secured the best results 40 and the least breakage from the use of a flexible grinding wheel one-eighth of an inch thick of 36 grit. The emery wheel 32 is mounted on the 45 end of the spindle 26 between two washers 33 which are clamped against the emery wheel 32 by the nut 34 that is threaded to the outer end of the spindle 26. The washers 33 may be entirely 50 of iron or steel although as an added precaution against wheel breakage we prefer those having a layer of resilient material such as the rubber 55 35 on the sides in contact with the emery wheel. The rubber 35 is preferably vulcanized to the metal washers 33 so it will not become loosened under strain such as that imposed by the breaking 60 of the emery wheel 32. The rubber 35 should be thick enough to imbed in the porous surface of the emery wheel with sufficient pressure to prevent the pieces of the emery wheel, 65 when broken, from being thrown out from between the washers 33 by centrifugal force.

Secured to the top of the shackle 14, by any suitable means such as fusion welding, is a holder 36 in which the free end of the flexible 70 shaft may rest when not in use, and secured to the free end of the flexible shaft and partially surrounding the emery wheel 32 is an emery wheel guard 37 of well known form.

The complete rail joint parting machine as 75 shown may be transported along a railroad track on the usual workmen's track car. It may be used while on the car or it may be carried along the track from joint to joint by means of the handle provided.

75 The gasoline engine power plant may be started

by winding a piece of strong cord around the starting pulley 38 and then giving it a quick pull thereby rapidly rotating the engine. After starting, the power plant should require no further attention.

The speed of the emery wheel 32 may be varied relative to that of the power plant by changing the belt 31 from one step to another of the cone pulleys 29 and 30. In case the belt 31 is too tight to shift readily from one step to the other it may be loosened by first loosening the set screw 28 and then screwing the support 27 downward in the socket 23. After the belt has been shifted it may be tightened by screwing the support 27 upward and then locking it in place by tightening the set screw 28 to preserve the setting. When the support 27 is screwed either up or down in the socket 23 the handled set screw 39 should be loosened so the support 27 may rotate freely in the countershaft 25 and then tightened after the adjustment is made to hold the pulley 30 on the countershaft in alignment with the pulley 29 on the power plant.

The method of using the rail joint parting machine described herein for removing weld metal 100 from rail joints and for removing the upper corner of rail ends is the same in each case. The machine is taken to the joint to be operated upon and started. Then the face of the rapidly rotating emery wheel 32 is held against the metal 105 to be removed until the desired amount has been ground off. In practice it has been found that this machine removes weld metal from rail joints or the upper corner of rail ends in a rapid and economical manner regardless of the hardness 110 of the metal.

The machine has numerous advantages over those in use heretofore. As it may be readily carried by hand it may be placed in a position where the work may be performed most advantageously, such as along side of the railroad track, where it need not be moved when a train passes. As it is entirely self-contained it may be used on roads that are not electrified and as it is not dependent during its operation upon the 120 car that transports it along the track it may be left at one point to perform its operation while the car goes to another part of the section.

As the weight of the power unit is distributed 125 centrally within the cradle it may be carried with a minimum amount of inconvenience, and as it is disposed within the outline of the cradle, a workman is not liable to danger from contact with a moving part and the machine is not liable to damage during handling. Also as the center 130 of gravity is low and well within the outline of the bottom of the cradle it will rest on an uneven surface without danger of becoming upset.

The fact that it may be positioned beside the railroad track when in use is of considerable 135 importance on roads where trains are frequent, and the fact that it is entirely self-contained renders it applicable to other kinds of work besides that for which it is especially adapted.

Various equivalent units may be substituted 140 for those shown and described herein and the arrangement of the units may be altered without departing from the invention or sacrificing any of the rights thereunder.

We claim:

1. In a portable grinding apparatus, a power plant and power transmission means, a pair of similar frame members arranged in laterally spaced relation and provided with means whereby they are connected at their tops and bot- 150

- 5 toms to provide a cradle substantially encompassing said power unit and power transmission means and providing a support therefor, a grinding tool, a driving connection between said power transmission means and said tool, and a carrying handle arranged longitudinally of said cradle above said power unit and power transmission means and supported by the means connecting the tops of the frame members, whereby the apparatus may be suspended for transportation, said frame members providing a support for the apparatus when it is at rest.
- 10 2. In a portable grinding apparatus, a cradle comprising two similar frame members, each provided with a horizontal bottom and upturned ends, means joining said bottoms and upturned ends, a power unit and power transmission means mounted on said members within and substantially encompassed by said cradle, a grinding tool, means providing a driving connection between said power transmission means and tool, and a carrying handle arranged longitudinally of said cradle and connected with said frame members by the means joining the up-
- 15 turned ends thereof and adapted for transporting said cradle and the parts carried thereby in suspended position, said horizontal bottoms affording a support for said cradle and parts when at rest.
- 20 3. In a rail joint parting machine, the combination of a portable cradle comprising a pair of substantially similar U-shaped members having their bottom sections parallel and spaced apart, and having their legs inclined toward a vertical plane between said sections; shackles connecting the legs at each end of said cradle; a carrying bar for said cradle in said plane and connected to said shackles; a power unit mounted within said cradle and having the base member thereof connecting said bottom sections; power transmission means comprising a substantially fixed portion in said plane connected to said unit within said cradle and a flexible portion outside of said cradle; and a rail parting grinding wheel secured to the free end of said flexible portion.
